E. F. HERSHBERGER.
THREADER, HOLDER, AND CUTTER FOR THREAD.
APPLICATION FILED JUNE 23, 1917.

1,240,142.

Patented Sept. 11, 1917.

Inventor
ELMER F. HERSHBERGER

By *Watson E. Coleman*

Attorney

UNITED STATES PATENT OFFICE.

ELMER F. HERSHBERGER, OF KOKOMO, INDIANA.

THREADER, HOLDER, AND CUTTER FOR THREAD.

1,240,142.

Specification of Letters Patent. Patented Sept. 11, 1917.

Application filed June 23, 1917. Serial No. 176,584.

To all whom it may concern:

Be it known that I, ELMER F. HERSHBERGER, a citizen of the United States, residing at Kokomo, in the county of Howard 5 and State of Indiana, have invented certain new and useful Improvements in Threaders, Holders, and Cutters for Thread, of which the following is a specification, reference being had to the accompanying drawings.

10 This invention relates to an improved threader, holder, and cutter for cotton thread, silk, and the like, and has for its primary object to provide a very simply constructed device which may be readily 15 attached to or removed from the thread spool.

It is another and more particular object of the invention to provide a device for the above purpose, constructed from a single 20 plate of sheet metal, the parts of which are cut and folded to provide a needle guide and means for retaining a threading hook in relation thereto, means for attaching the device to a spool, a holding clip for the 25 thread, and means for cutting the thread.

It is a further general object of my invention to improve and simplify the construction of devices of the above character and render the same highly efficient and 30 serviceable in practical use.

With the above and other objects in view, my invention consists in the novel features of construction, combination, and arrangement of parts to be hereinafter more fully 35 described, claimed and illustrated in the accompanying drawing, in which,

Figure 1 is a perspective view showing my improved combination threader, holder, and cutter applied to a thread spool;

40 Fig. 2 is an enlarged elevation illustrating the manner of threading the needle and showing the needle in dotted lines disengaged from the threading hook;

Fig. 3 is a sectional view taken on the 45 line 3—3 of Fig. 2; and

Fig. 4 is a plan view of the blank from which the device is formed.

Referring in detail to the drawing, 5 designates the metal blank from which the device is formed, said blank being stamped or 50 cut out of sheet metal to provide the elongated portion 6, a rectangular portion 7 projecting laterally from one end of the body portion 6 and connected thereto by a 55 relatively short neck having obliquely in-

clined side edges 8. The plate is slit or cut inwardly for a short distance, as at 9, from the meeting point of these inclined edges 8 with the opposite edges of the rectangular portion 7. The purpose of such construction will be presently stated.

The elongated body portion 6 of the blank is also provided with the spaced tongues 10 projecting laterally from its opposite longitudinal edge, and a short finger 11 is 60 formed upon the edge of one of the tongues 10 and projects at right angles thereto. A finger piece 12 is also formed upon the end edge of the body 6 between the finger or extension 11 and one of the inclined edges 65 8. The edge of the plate at the notch 13 formed by the juncture of the finger piece 12 with its inclined edge 8, is sharpened to provide a cutting edge.

The opposite end of the body 6 is adapt- 75 ed to be turned over, as at 14, and clenched upon the shank of the threading hook 15. The plate 6 is also adapted to be folded upon itself along the dotted lines indicated at 16 and 17 respectively.

After the threading hook is secured in the end 14 of the plate 6, said plate is folded upon the dotted line 16 so as to position the hook shank exactly in line with the space between the adjacent edges of the 85 tongues 10. The plate is then folded in the same direction along the dotted line 17. In this latter folding operation, the tongues 10 will be disposed with their side faces in opposed relation and the hook bill, indicated at 18, will be located contiguous to the side edges of said tongues and between the same. The finger or projection 11 is 90 then bent over upon the edge of the other tongue 10 and its extremity outwardly 95 curved to provide a clamping clip for the thread. The finger piece 12 is now bent at right angles to the plane of the body plate.

Finally, the side portions of the rectangular part 7 of the plate are turned inwardly 100 to provide an open, resilient sleeve 19, and the plate then bent at the juncture of the sleeve with the body to dispose the sleeve at right angles to said plate. The sleeve 105 19 is adapted for insertion into the end of the bore of the thread spool indicated at 20, so that the plate 5 will lie flat upon the end face of the spool with the ends of the tongues 10 projecting slightly beyond the periphery of the spool flange. In the inser- 110

tion of the sleeve within the spool bore, the end portions of the sleeve are compressed toward each other, and when released, they will exert an outward pressure against the 5 spool. In this manner, it will be appreciated that the device will be securely, though detachably retained in position upon the spool.

In the practical use of my invention, the 10 needle indicated at N is inserted between the ends of the opposed tongues 10 and drawn laterally over the hook bill 18 until said hook bill is engaged through the eye of the needle. The thread shown at T is 15 then also engaged under the hook bill between the same and the needle eye. After the requisite amount of thread has been drawn from the needle eye, the thread is engaged beneath the clip 11 and around the 20 finger piece or extension 12 to the cutting edge 8. In order to cut or sever the thread, it is drawn taut against the sharpened edge 13 of the plate, and the free end of the thread may then be readily grasped to withdraw additional thread from the spool, if 25 desired. When the thread is not being used, the needle may be first threaded and impaled through the thread on the spool, the thread extending from the needle beneath 30 the clamping clip 10 and being held taut thereby.

From the foregoing description, taken in connection with the accompanying drawing, the construction, manner of operation, and 35 several advantages of the device will be clearly and fully understood. As the device is constructed from a single sheet metal plate, it will be appreciated that the same can be produced at very small manufacturing cost. The article may be constructed in any desired size, and while I have herein shown and described the preferred form and relative arrangement of its several parts, it is manifest that the same are susceptible of 40 considerable modification and I, therefore, reserve the privilege of adopting all such legitimate changes as may be fairly embodied within the spirit and scope of the invention as claimed.

50 Having thus fully described my invention, what I desire to claim and secure by Letters Patent is:

1. A device of the character described comprising a body plate having opposed 55 tongues formed thereon constituting a needle guide, a needle threading hook fixed to said plate and disposed adjacent to one edge of said tongues, the opposite edge of one of said tongues being provided with a thread holding clip, and an expandible sleeve on

said plate for detachable engagement in the bore of a thread spool.

2. A device of the character described comprising a body plate having opposed 65 tongues formed thereon constituting a needle guide, a needle threading hook fixed to said plate and disposed adjacent to one edge of said tongues, the opposite edge of one of said tongues being provided with a thread holding clip, said body plate being provided upon one end with an angularly disposed finger piece and having an obliquely inclined edge constituting a guide for the thread, said plate at the juncture of the finger piece with said oblique edge thereof 70 being sharpened, and an expandible sleeve on said plate for detachable engagement in the bore of a thread spool.

3. As an improved article of manufacture, a needle threader body consisting of a single 80 sheet metal plate having an elongated portion, one end of said elongated portion being adapted to be pinched upon the shank of a threading hook, spaced lugs extending laterally from the other end of said elongated portion, a rectangular portion connected by a tapering neck to the opposite longitudinal edge of said elongated portion, the plate being cut inwardly at the juncture 85 of the rectangular portion with said neck, said plate being adapted to be folded upon itself to dispose said tongues in opposed relation and position the threading hook in line with the space between said tongues at one edge thereof, the edges of said rectangular portion of the plate being adapted to be bent inwardly toward each other to provide an expandible sleeve for insertion into the bore of a thread spool, and a thread 90 holding clip formed upon the edge of one of said tongues and adapted to be bent over upon the face of the other tongue.

4. A device of the character described comprising a body plate having opposed 95 tongues formed thereon constituting a needle guide, a needle threading hook fixed to said plate and disposed adjacent to one end of said tongues, and an expandible sleeve integrally formed with the plate and extending 100 at right angles to the plane thereof, said plate being adapted for detachable engagement in the bore of a thread spool and the body plate being engaged upon the end face of the spool.

In testimony whereof I hereunto affix my 115 signature in the presence of two witnesses.

ELMER F. HERSHBERGER.
